Attorney

UNITED STATES PATENT OFFICE.

ANTONIO CERCONE, OF BURLINGTON, VERMONT.

MUSICAL INSTRUMENT.

1,288,382.

Specification of Letters Patent. Patented Dec. 17, 1918.

Application filed July 24, 1918. Serial No. 246,560.

To all whom it may concern:

Be it known that I, ANTONIO CERCONE, a citizen of the United States, residing at Burlington, in the county of Chittenden and State of Vermont, have invented certain new and useful Improvements in Musical Instruments, of which the following is a specification, reference being had to the accompanying drawings.

10 This invention relates to musical instruments, and particularly to music boxes.

The general object of the invention is to provide a very simple music box which is designed as a child's toy.

15 A further object is to provide a music box of this character which is very simple in construction, may be easily operated, and which is not liable to be readily damaged.

Other objects will appear in the course of 20 the following description.

My invention is illustrated in the accompanying drawings, wherein—

Figure 1 is a longitudinal sectional view of a musical instrument constructed in accordance with my invention;

Fig. 2 is a longitudinal sectional view taken on a plane at right angles to Fig. 1;

Fig. 3 is an end view of the instrument;

30 Fig. 4 is a section on the same lines as Fig. 2 but showing a modification in the structure.

Fig. 5 is a fragmentary transverse sectional view through the hammers 18 and the strips 14 to show the detailed construction 35 of the hammers.

Referring to these figures, 10 designates the body or case of the music box, which is rectangular in cross section and which tapers from one end to the other. The ends 40 of the casing are closed by the end pieces 11 and 12, the end piece 12 being formed with a preferably arcuate and more or less ornamental opening 13. This end piece 12 may be readily removed from its engagement 45 with the body of the casing. Disposed within the body of the casing are a plurality of resilient strips or rods, designated 14, these rods being attached to one wall of the casing 10 by means of an attaching strip 15, and 50 inward of this attaching strip there is disposed a bridge or rib 17.

As before remarked, these strips 14 are resilient and carry at their free ends the hammers 18. The strips project beyond the 55 hammers, as at 19, and coacting with these

projecting ends of the strip is a shaft 20 provided with a plurality of tappets 21 disposed in line with the projecting ends of the strips 14. As illustrated, these tappets project at diametrically opposite points from the shaft 60 20 so that when the shaft is rotated, each of these strips is lifted and let fall twice for each rotation of the shaft. The shaft 20 is rotated by means of a crank handle 22 and mounted upon the shaft is a ratchet wheel 65 23 engaged by a longitudinally extending spring 24 mounted upon one side wall of the casing 10.

The strips 14 have different lengths or are made of different materials or otherwise 70 constructed so as to have different rates of vibration and when the hammers strike the wall of the casing, these strips will be caused to vibrate and give forth a musical sound. If these strips themselves do not give forth 75 a musical sound, still the action of the hammers upon the side wall of the casing will be to give a drumming sound, whose pitch will be determined by the quality of the wood of which the casing is made and by 80 the size of the casing and the column of air contained therein. It is also obvious that strings or metallic strips may be disposed within the casing so as to be struck by these hammers and I have illustrated such a construction in Fig. 4, wherein the strings are 85 designated 25.

While I have before referred to the strips 14 as being the means whereby musical notes are sounded on this instrument, yet by 90 forming the hammers 18 of different shapes or forming these hammers with differently shaped recesses, as illustrated in Fig. 5, variations in sound may be produced when the hammers strike the wood of the box or 95 case, the wood of the box or case thus acting as a sounding board.

It will, of course, be understood that any number of hammers or strips 14 may be used and thus increase the range of the instrument.

The operation of this device will be readily understood. It is supported in any suitable manner and the handle is rotated thus causing the tappets to intermittently lift the 105 strips 14 and their hammers and then let the hammers fly back again against the wall of the box or against the strings, if strings are used. It will be obvious that a device of this character may be made in all sizes and that 110

it may have a large or a small range of sound or pitch so that different tunes may be played upon it.

Having described my invention what I claim is:—

- 5 1. A musical instrument of the character described comprising a casing, a plurality of resilient strips attached at one end to one side wall of the casing and carrying hammers, a shaft extending through the casing and having tappets engageable with the respective strips, the shaft being rotatable, the hammers having differently shaped recesses in them to thereby cause the hammers to
- 10 15 produce different notes when they strike the wall of the casing.

- 20 2. A musical instrument of the character described comprising a casing forming a sound box gradually tapering from one end to the other, the end wall at the small end of

the casing being imperforate, the opposite end wall having an opening, a plurality of resilient strips attached to the wall of the casing on the inside thereof and adjacent the small end of the casing and extending 25 toward the large end, the free end of each strip carrying a hammer, a shaft extending transversely across the casing and through the side walls thereof and having a plurality of tappets thereon disposed entirely within 30 the casing and engageable with the strips to intermittently raise and release the strips as the shaft is rotated, and means for rotating the shaft.

In testimony whereof I hereunto affix my 35 signature in the presence of two witnesses.

ANTONIO CERCONE.
